UNITED STATES PATENT OFFICE

146,442

DESIGN FOR A FLOATING TOY

John H. Wright, Philadelphia, Pa.

Application August 2, 1946, Serial No. 132,249

Term of patent 14 years

(Cl. D34—15)

To all whom it may concern:

Be it known that I, John H. Wright, a citizen of the United States of America, resident of Philadelphia, Pennsylvania, have invented a new, original, and ornamental Design for a Floating Toy, of which the following is a specification, reference being made to the accompanying drawings, forming a part thereof.

Referring now to the drawings, Fig. 1, Fig. 2 and Fig. 3 are elevational views of a floating toy embodying my new design in three different positions, and Figs. 4 and 5 are top perspective views of the same from different angles.

I claim:

The ornamental design for a floating toy, substantially as shown.

JOHN H. WRIGHT.
